UNITED STATES PATENT OFFICE

164,232

HOSE REEL CART

Stanley A. Germain, Glendale, Calif.

Application July 29, 1950, Serial No. 11,484

Term of patent 3½ years

(Cl. D14—3)

To all whom it may concern:

Be it known that I, Stanley A. Germain, a citizen of the United States, residing at Glendale, in the county of Los Angeles and State of California, have invented a new, original, and ornamental Design for Hose Reel Cart, of which the following is a specification, reference being had to the accompanying drawing, forming part thereof.

The drawing figure is a perspective view of a hose reel cart showing my design.

I claim:

The ornamental design for a hose reel cart, substantially as shown.

STANLEY A. GERMAIN.
